UNITED STATES PATENT OFFICE.

EDWARD FISHER GOBEN, OF MUSKOGEE, OKLAHOMA, ASSIGNOR OF ONE-HALF TO
PRESLEY R. ALLEN, OF MCALISTER, OKLAHOMA.

RAIL-BENDER.

1,342,263.

Specification of Letters Patent.

Patented June 1, 1920.

Application filed August 17, 1917, Serial No. 186,751. Renewed December 1, 1919. Serial No. 341,797.

To all whom it may concern:

Be it known that I, EDWARD F. GOBEN, a citizen of the United States, residing at Muskogee, in the county of Muskogee and 5 State of Oklahoma, have invented new and useful Improvements in Rail-Benders, of which the following is a specification.

This invention relates to a rail bender particularly adapted for use in bending mine 10 rails, and one object of the same is to provide a bending mechanism of the class specified of a readily portable character having means particularly applied thereto for effecting an anti-frictional movement to render 15 the operation of the main bending element easy and at the same time positive. A further object of the invention is to provide a rail bender with means for bending a rail either to give a convex or a concave 20 configuration thereto, and to so construct the several parts that they may be readily operated to cause the rail bending element to shift and change movement automatically through the medium of a hand oscillating 25 means which is readily reversible to produce and apply the bending pressure on the rail either in an inward or an outward direction. A still further object of the invention is to provide a rail bender having a shiftable rail 30 bending member automatically operated by a manually controlled oscillating mechanism to secure the bending arc desired and without liability of injury to the rail.

In the drawings:

35 Figure 1 is a perspective view of a rail bender embodying the features of the invention, and shown as looking upwardly from the lower side thereof.

40 Fig. 2 is a top plan view of the improved rail bender shown applied and the hand bar detached therefrom.

Fig. 3 is a section taken on the line 3. 3. Fig. 2 with the hand bar applied.

45 Fig. 4 is a section taken on the line 4. 4. Fig. 2, one of the rail holding arms being broken away.

50 Fig. 5 is a detail sectional elevation of the ratchet dog and a part of the ratchet disk co-operating therewith and shown in upright position and at a different angle to that shown by Fig. 6.

Fig. 6 is a horizontal section taken in the plane of the line 6. 6. Fig. 5.

55 Fig. 7 is a perspective view of the rail bender partially broken away and showing

a bending attachment applied thereto for straightening bends in rails.

The numeral 5 designates a yoke having a centrally enlarged body 6 substantially of circular form as shown and from which 60 arms 7 extend and are bent at right angles and terminating in heads 8 with slots 9 having a contour simulating the head and part of a web of a rail. Extending from the yoke 5 at points where the arms 7 emanate 65 from the body 6 are supports 10 for a flat cap or head disk 11, the supports 10 being bored longitudinally as at 12, see the dotted lines in Fig. 2, and through the portions of the arms 7 adjacent to the body 6 and the 70 said supports 10 and reduced ends 13 of the cap or disk 11 bolts 14 are inserted and have their ends engaged by nuts 15 bearing on the reduced ends 13 of the cap or disk. The bolts 14 have their heads countersunk 75 in the arms 7 adjacent to the body 6 and these bolts may be readily removed by detaching the nuts 15 to permit dissociation of the cap or disk 11 when desired for repair or other purposes. Between the cap or 80 disk 11 and the body 6 a ratchet wheel or disk 16 is mounted and has the opposite sides formed with grooves 17 which are respectively adjacent to the inner opposing sides of the said body 6 and cap or disk 11. 85 The grooves 17 form ball races for a series of anti-friction balls 18 which bear against the inner opposing sides of the body 6 and the cap or disk 11. The ratchet wheel 16 is formed with peripheral grooves 19 at opposite sides of the teeth 20 thereof as clearly 90 shown by Fig. 3, and therein rings 21 are loosely seated and free to move. The rings 21 are respectively formed with projections 22 and 23, the projection 22 having side 95 flanges 24 to form a boxing, and with the remaining projection 23 the said projection 22 provides a socket for a removable hand bar or lever 25. The two projections 22 and 23 have a bracket arm 26 interposed therebetween and secured by small bolts 27 to the projections adjacent to the rings, the arm 26 being curved and terminating in an outwardly projecting angular tubular member or cylinder 28 which stands in diametrical relation to the ratchet wheel 16. The bracket arm 26 with its tubular member or cylinder 28 moves uniformly with the rings 21, these parts having an oscillating movement imparted thereto by the similar move- 100 105 110

ment of the hand bar 25. Within the tubular member or cylinder 28 a dog or pawl 29 is mounted and has a reduced end 30 normally projected inwardly beyond the inner end of the said member or cylinder 28 to engage the spaces between the teeth 20 of the ratchet wheel 16 to cause the latter to rotate in one direction of movement and in accordance with the adjustment of the 5 said dog or pawl 29. The dog or pawl 29 has a reduced shank or stem 31 extending through a movable locking cap 32 fitted in the outer end of the tubular member or cylinder 28. The formation of the stem or 10 shank 31 provides a shoulder 33 at the outer terminal of the dog or pawl 29 and the outer end of the cylinder has an inner annular shoulder 34. Between the shoulder 33 of the dog or pawl 29 and the annular shoulder 15 34 of the member or cylinder 28, a spring 25 is mounted and surrounds the stem or shank 31, said spring operating to project the dog or pawl inwardly in normal operating position. The cap 32 has diametrically 20 opposed locking lugs or projections 36 which are adapted to be seated in opposite slots 37 formed in the outer end of the tubular member or cylinder 28. The dog or pawl 29 is rotatable with the said cap to disengage the 25 30 catch lugs 36 from the slots 37 and the said dog or pawl may be reversed so as to cause a reversal of operation of the ratchet wheel or disk 16.

The arms 7 with their slotted heads 8 constitute means for applying and holding the bender or bending mechanism in fixed position relatively to the rail operated upon, and a bending element engages the ratchet disk or wheel 16. This bending element 35 40 consists of a screw stem 38 having a head 39 with a slot 40 of the same form and opening outwardly through the head in a manner similar to the slots 9 of the heads 8 of the arms 7. The screw stem engages openings 41, 42, and 43, respectively formed in the cap or disk 11, the center of the ratchet disk or wheel 16 and the body 6 of the yoke 5 as clearly shown by Fig. 3. The openings 41 and 43 have smooth walls, and the opening 42 is threaded. The bending element 45 50 constructed as just explained is located centrally between the arms 7 of the yoke 5 and is movable inwardly and outwardly through the cap or disk 11, ratchet disk or wheel 16 and body 6 in accordance with the feeding movement of the said ratchet disk or wheel 16 and which is regulated by the position of the dog or pawl 29 relatively to the teeth 20 of the said ratchet disk.

In applying the bender or bending mechanism, the rail to be bent is suitably supported on its base flange and the heads 8 of the arms 7 are applied over the ball or head and web portion of the rail and at the same time 60 65 the head 39 of the bending element is caused

to similarly engage the rail between the points of engagement therewith of the heads 8. The dog or pawl 29 is then turned so as to cause a feeding operation of the ratchet disk or wheel 16 relatively to the screw stem 38 to effect an inward or an outward bend of the rail as may be desired. It will be understood that the socket for the hand bar 25 will be uppermost and when the bender or bending mechanism has been applied as 70 75 just explained, the operator inserts the hand bar or lever 25 in the socket forming part of the rings 21 and then oscillates the said ratchet disk or wheel 16 to cause the screw stem 38 to gradually feed or move through 80 the parts engaged thereby and bend the rail, the dog or pawl 29 firmly biting in between the teeth 20 of the ratchet disk or wheel in one direction of the movement of the latter and slips over the said teeth in the reverse 85 movement. In view of the attachment of the bracket arm 26 to the projections 22 and 23 of the rings 21 the said arm and the tubular member or cylinder 28 move equally with the said rings and the dog or pawl 29 90 is regularly and positively caused to engage the teeth 20 to exert a pulling action thereon in either one of two directions in accordance with the adjustment of the said dog or pawl. The anti-frictional balls 18 95 render the operation of the ratchet disk or wheel 16 very easy and materially lighten the power required to actuate the bending element engaging the said ratchet wheel.

In Fig. 7 a bending attachment is shown 100 applied and in operative relation to the bender and consists of a yoke comprising a lower horizontal member 44 and side arms 45 with slots 46 adjacent to the free ends thereof and through it pull bar 47 is removably mounted. In this instance the heads 8 of the arms 7 of the bender are terminally formed with concave recesses or seat depressions 48, one in each, to permit said heads to be applied over and snugly engage the ball of the rail. The bender is not modified in any other particular, and the operation thereof is precisely the same as in the preceding disclosure. The object of this attachment is to straighten rails that have surface bends, as at 49, and in the use of the attachment in straightening rails of this type, the yoke is caused to engage the rail in the manner shown in Fig. 7 and with the lower horizontal member 44 under the base 110 flange of the rail immediately beneath the surface bend, the arms 45 of the yoke extending upwardly at opposite sides of the rail with the pull bar 47 in place in the slots 46. The pull bar 47 is also inserted 115 through the slot 40 of the head 39 of the screw stem 38, the heads 8 of the arms 7 of the bender being rested on the ball of the rail as shown. By operating the screw stem 38 to feed the screw upwardly by means of 120 125 130

the ratchet mechanism hereinbefore described the rail with the surface bend will be gradually straightened and repair of the rail will thus ensue without cutting out the 5 surface bend portion as is the usual custom. By the means of the attachment, waste of material is avoided and a rail with a surface bend may be quickly repaired or restored to normal working position.

10 The improved bender or bending mechanism is light in structure and readily portable; may be quickly applied to and released from a rail; is strong and durable, and comparatively inexpensive in its construction.

15 What is claimed is:—

1. A rail bender of the type having a yoke with rail-engaging arms and an intermediate body with a cover disk held in fixed spaced relation to the intermediate body, a 20 ratchet disk between the said body and cover disk provided with grooves in the opposing faces loosely engaged by rings having flanges forming a socket to receive means for operating the rings on the ratchet disk and 25 also provided with projections, a bracket arm interposed between and secured to the projections of the rings and carrying a cylinder extending at an angle therefrom and radially to the ratchet disk, the said 30 cylinder having a spring-controlled pawl reversibly inclosed therein, and means movably engaging the outer free end of the cylinder and connected to the outer end of the stem of the pawl for reversing the latter in 35 the cylinder and locking it in its adjusted position.

2. A rail bender of the type having an intermediate body with an opening therethrough, a cover disk secured to and spaced 40 from the body, a ratchet disk mounted and freely movable between the cover disk and body, the body having rail-engaging arms

and the ratchet disk provided with rings loosely mounted thereon and also embodying a bending element having a screw stem movable through the centers of the cover disk, the ratchet disk, and the opening of the said body, combined with a cylinder connected to portions of the rings and disposed 45 radially with respect to the center of the ratchet disk, the said cylinder having a spring-actuated pawl reversibly mounted therein, the cylinder having an outer rotatable locking cap to which the stem of the 50 pawl is secured, the pawl being movable outwardly through the outer end of the cylinder and having a spring thereon between the cylinder and the pawl.

3. A rail bender of the type having arms 60 with heads formed to engage the ball of the rail and an intermediate screw stem and head provided with ratchet and pawl operating mechanism therefor, combined with a bending attachment for removable engagement 65 with the head of the intermediate screw stem, said bending attachment being adapted to straighten a surface bend of a rail and consisting of a U-shaped yoke having a rigid base and parallel rigid arms at 70 right angles thereto, the base and arms always remaining in the same fixed relation and the arms adjacent to their free ends being provided with slots therethrough, and a pull bar loosely mounted in the slots of the 75 arms of the yoke and removably engaged by the head of the intermediate screw stem between the ends of the arms of the yoke.

In testimony whereof I have hereunto set my hand in presence of two subscribing witnesses.

EDWARD FISHER GOBEN.
